UNITED STATES PATENT OFFICE.

WILFRED JOHN DAVIS, OF PLYMOUTH, ENGLAND, ASSIGNOR TO RADIO CORPORATION OF AMERICA, A CORPORATION OF DELAWARE.

CALLING DEVICE FOR WIRELESS TELEGRAPHY.

Application filed November 3, 1921, Serial No. 512,439, and in Great Britain December 20, 1920.

The object of this invention is to provide improved apparatus by which an alarm can be automatically given on the receipt of a predetermined combination of Morse characters such as the international distress signal S. O. S. (• • • - - - • •), for example although the arrangement may be adjusted to respond to any prearranged combination.

According to this invention a relay A is provided in a receiving circuit, say, in the anode circuit of a valve (not shown), and each time this relay is closed a current is caused to pass through a slow acting relay B which only closes for a dash but not for a dot. This slow acting relay B controls the circuit of an electromagnet D which is accordingly only energized by dashes. In parallel with the slow acting relay is a second electromagnet F energized by both dots and dashes, and in series with both the electromagnets D and F is a set of contacts all of which shortcircuit a bell or other alarm. The two electromagnets D and F are arranged to open these contacts so that when the predetermined combination is received all the contacts are opened and the bell or other alarm will be actuated, but this will not occur unless the predetermined combination is received.

The shortcircuiting of the bell or other alarm is controlled by means of the following apparatus:—

A ratchet wheel having fast with it a disk is turned one tooth by the second electromagnet F each time it is energized, that is, for each dot and each dash. Around the periphery of the disk are arranged spring plungers which can move parallel to the axis and the number of which is equal to the number of teeth on the ratchet wheel. Adjacent to each plunger is a spring finger pivoted to the disk and adapted, on any plunger being moved outwards from the face of the disk to slip in under the head of the plunger to lock and keep it protruding from the face of the disk. As the disk is rotated these plungers pass in turn before the armature lever D' of the first electromagnet D with the result that whenever that magnet is energized by the receipt of a dash, a plunger is moved outwards from the face of the disk and its locking finger slips behind its head and keeps it out. Just before a plunger is carried by the rotation of the disk

past the first magnet the end of its locking finger comes against a fixed stop K or N 55 which withdraws any finger that may happen to be beneath the head of a plunger and thus allows the plunger to be returned by its spring to its normal position. On the receipt of the predetermined combination, say, 60 S. O. S. there will be a sequence of plungers on the disk in the following order: Three in, three held out, three in. Opposite the plungers of this sequence in the position they occupy as soon as the sequence has been completed 65 is an equal number of spring contact plungers carried by a fixed bracket. The middle three contact plungers control three of the short circuiting contacts G which are normally closed and these three will be pushed out by 70 the heads of the protruding plungers at the middle of the sequence that has been set up on the disk and therefore these three contacts will be opened. The other contact plungers Q on the bracket are adapted to 75 make electrical connection with the head of any protruding plunger I which may be opposite them, that is, the six dot contacts are normally open but are closed when there is a protruding plunger on the disk opposite 80 one of the six plungers on the bracket. When, however, the required sequence has been set up none of the plungers I on the disk opposite the six plungers Q on the bracket will be protruding and therefore all the nine contacts will be open and the bell or other alarm 85 will be actuated. Unless, however, the predetermined combination of signals has been received some one or more of the contacts will be closed and therefore the bell or other 90 alarm will not be actuated. When all the contacts are open the bell or other alarm which had previously been shortcircuited is connected in series with the second electromagnet F and the current through this magnet is thereby reduced sufficiently to prevent any further rotation of the ratchet wheel and disk. The contacts therefore remain open 95 and the alarm continues to be actuated so long as signals are received.

In place of the first electromagnet attracting a plunger it may be caused to actuate a spring lever which pushes the plunger outwards from the disk as shown in Fig. 2.

The slow acting relay may be an ordinary 105 electromagnet having stout copper bushes

around the pole tips, so that the eddy currents set up in the copper retard the building up of the magnetic flux.

If it is desired to include in the sequence which is to give the alarm the necessary inter-letter spaces at the beginning and end of the S. O. S. signal, a slow acting space relay C may be provided to control the circuit of an electromagnet E which will only be energized by inter-letter spaces and not by the spaces between the elements of a letter.

The following detailed description and accompanying drawings show one way the apparatus could be arranged to give an alarm on receipt of the International distress signal (• • • - - - • • •) preceded and ended by a space not shorter than the space between letters of the Morse code; the complete signal could therefore be written down as "space, dot, dot, dot, dash, dash, dash, dot, dot, dot, space."

The invention is illustrated by the accompanying drawings, Fig. 1 of which is a diagram showing the connections, Fig. 2 is a side elevation in partial section of the apparatus, Fig. 3 is a face view of the disk along the section line III. III. of Fig. 2, Fig. 4 is a rear view of the apparatus and Figs. 5 and 6 are sections on the lines 5-5 and 6-6 of Figure 4. Figure 7 is a diagram showing a modification.

In Fig. 1 A is a signal relay the coils of which are in the anode circuit of a receiving valve so that the tongue T follows the dots and dashes of the incoming signals. In series with the tongue T and marking contact M of this relay is a delayed action marking relay B connected to a battery A', while connected in series with the tongue T and spacing contact S is a delayed action spacing relay C also connected to the battery A'. The contacts of these delayed action relays B and C do not close until some little time after the contacts T and M and T and S respectively close. The relay B is adjusted to close for a dash and not for a dot, while the relay C is adjusted to close when a space at least equal to that between letters is received but to remain open for the shorter spaces between elements of a letter. In series with the contacts of relays B and C are two electromagnets D and E; it will be seen that D, the dash magnet, is only energized when a dash is received, while E, the space magnet, is only energized when an inter-letter space is received. Also connected in series with T and M and in parallel with relay B is a ratchet controlling magnet F which is operated whenever T contacts with M. A number of contacts G in parallel with a bell X or other form of alarm or recording device connected across them are inserted in series with B, C, D, E and F, therefore every time contacts T and M of the signal relay A close, a current will flow round the coils B and F and across

such of the contacts at G as are closed. If the contacts T and M remain closed for a longer period than is represented by a dot then the contacts of relay B close and D is energized. When contacts T and S close them the circuit through B, D and F is broken, while a current passes through relay C and across contacts G; if contacts T and S remain closed for a longer period than is represented by the space between the dots or dashes of a letter, then the contacts of C close and magnet E is energized. So long as one or more of the contacts at G are closed the bell is short circuited and cannot ring but when all these contacts G are open the current passes through the bell which therefore rings when the contacts T and M or T and S of relay A close.

An arrangement for controlling the contacts G is shown in Fig. 2 in which H is a disk which is preferably made of aluminum to reduce its momentum and which has a number of plungers I, 1 to 24 fitted round its periphery. Each plunger is kept in position by a spring J under compression which pulls the head of the plunger on to the face of the disk. The disk is fast on a spindle O which has also fast with it a ratchet wheel L having a number of teeth (24) equal to the number of plungers on the disk; a pawl P operated by the magnet F engages with this wheel and every time the tongue of relay A returns to its position of rest after having been moved by a dot or dash, that is to say, every time the contacts T and M open, the disk H is rotated through one tooth of the wheel L.

Pressed against the head of each plunger by a spring r is a light locking finger R (Fig. 3) so that when a plunger is pushed outward from the disk the finger R will slip in under its head and so prevent the plunger from returning to its normal position when released.

When either of the magnets, D, E, is energized its armature D' or E' pushes the plunger I which is opposite it outwards from the face of the disk H. When the magnet is de-energized the armature releases the plunger but its finger R has, however, by this time slipped in under the head I of the plunger so that the plunger cannot return to its normal position but remains projecting from the face of the disk. Every plunger is reset to its normal position by the fixed stops K and N immediately before passing in front of either of the armatures.

It is required that the alarm bell shall ring after the signal (• • • - - - • • •) has been received. Before the first dot commences there is a "space"; that means that the tongue T and spacing contact S of the relay A are closed for an appreciable period so that the contacts of the delayed action spacing relay C close. The space magnet E is therefore energized and let us assume that plunger I' is pushed outwards by the space lever or ar-

- mature lever E' and locked by its finger R . As soon as the signal commences the contacts T and S open and the space lever or armature is released and remains so until the end 5 of the signal and the plungers I_2 to I_{10} which rotate in a counter-clockwise direction as indicated in Figure 3, and passed by armature E' are not actuated. When the space after the last dot occurs the plunger I_{10} is actuated. 10 The first three dots of the signal close the contacts T and M of relay A three times and after each dot is completed it causes the disk H to be rotated through one tooth of the ratchet wheel L by closing the relay F without 15 the operation of the dash relay of the movement of plungers I_{13} , I_{14} , I_{15} ; now when the first dash comes along the contacts of the relay B close, this causes the dash magnet D to be energized and the plunger I_{16} which 20 is in front of D is therefore pushed outwards from the disk. When the dash ends the disk is rotated through one tooth. The other two dashes act similarly to push plungers I_{17} , I_{18} outwards. The last three dots cause the disk 25 to be rotated through three teeth and plungers I_{19} , I_{20} and I_{21} are not affected because the dash magnet is not energized. A dot merely causes the disk to be subsequently rotated through one tooth of the ratchet wheel, while 30 a dash causes a plunger to be pushed outwards as well as subsequently rotating the disk through one tooth. As soon as the signal is finished, the space at the end causes the contacts of the delayed action spacing relay C to close and the plunger I_{10} in front of the armature spacing magnet is pushed 35 outwards. Hence, after the signal (•••---•••) has been received the five shaded plungers I_1 , I_{10} , I_{16} , I_{17} , I_{18} , as shown in Figure 3, 40 will project from the face of the disk. The other plungers corresponding to the dots and to the short inter-element spaces between the dots and dashes of the signal are in their normal position. 45 If any deviation in spacing or signalling occurs, however, even if it effects only a single plunger to move it out of proper position, the arrangement of switches on the insulating bracket V will prevent the current from 50 flowing through the bell X and it will be necessary to start a new series of signals of the proper sequence. Plungers I_{11} , I_{12} , I_{22} , and I_{24} are extra plungers and in the illustration given, no short circuiting devices are 55 used in conjunction therewith. In front of the disk H is a fixed insulated bracket V , Figure 4, carrying 24 spring contact plungers Q . Five of these contact plungers, which 60 occupy positions corresponding to the shaded plungers in Figure 3, cause spring contacts B to be normally closed as shown in Fig. 5 so that any projecting plungers which pass in front of them tend to open these contacts, while the remaining 19 contact plungers as shown in Fig. 6 make electrical contact 65 with the heads of any projecting plungers I on disk H which pass in front of them, i. e. these 19 contacts between plungers I and Q are normally open and only closed when there is a plunger I projecting in front thereof. All these 24 contacts are joined in parallel and are the contacts represented diagrammatically at G , Fig. 1. It will therefore be seen that when the correct signal has been received giving the disposition of the 70 plungers; as shown in Fig. 3, all the 24 contacts are open, the "three dash" and "two space" contacts being pushed open by the projecting plungers in front of them, while the remaining 19 contacts are open because 75 there are no projecting plungers in front of them. When all these contacts are open, the bell X which has previously been short circuited is connected in series with the magnet F . This reduces the current through this 80 magnet sufficiently to prevent any further rotation of the disk H . The contacts C therefore remain open and the bell rings every time the contacts T and M or T and S of the signal relay A close; if the sending continues 85 the bell rings out the incoming signal while if the sending stops the bell rings continuously. 90
- It is obvious that this explanation has been applied to specifically mentioned plungers 95 only for the purpose of illustration. Any one might be the first in the signal series, since, after the plungers have passed either stop K or N they are restored to their normal position. It is apparent that while any signals are being received that the disk H is in 100 constant rotation but the bell is not energized because the proper combination and sequence is not obtained. In case of this S. O. S. signal described, the last three plungers have no 105 function so that the position of the first nine counting from the stops K and N are the ones which control. From this it is seen that a continuous operation is maintained and no attention is required when once the device is 110 placed in operation.
- After the bell has been operated to sound the alarm the apparatus may be reset by simply pushing in one of the short circuiting switches as at G which allows sufficient current to pass through the magnet F to start the disk in rotation and the device in operation as before. 115
- By suitably placing the dash, space and other contacts on the fixed bracket V it can be 120 arranged that the bell shall ring after any desired combination of dots and dashes and inter-letter spaces is received.
- One type of delayed action relay is an ordinary electro-magnet which has stout copper bushes round the pole tips. The eddy currents set up in the copper retard the building of the magnetic flux. The armature of the relay is therefore not attracted until some 125 little time after the current is started through 130

the windings. This type of relay works satisfactorily so long as the current through the windings remains constant; if, however, the supply voltage increases or decreases by a small percentage the adjustment is completely upset.

An arrangement in which the delay is constant over a wide range of voltage is described below. In Figure 7 T and M are the tongue 10 and marking contact respectively by the signal relay; these contacts close for the dots and dashes of the signal. In series with these contacts and with a battery is a relay 1 whose tongue 2 normally makes contact with a contact 3, but when T and M close 1 is energized and 2 and 4 make contact. 2 therefore follows the dots and dashes of the incoming signal connected in parallel with relay 1 but also in series with 2 and 3 is a second relay 15 B whose tongue 5 is normally in contact with a contact 6. A coil D which it is required shall only be energized by a dash is connected in series with the contacts 4, 5 and 6. The action is as follows:

25 Suppose T and M close for a period represented by a dash, a current passes through relays 1 and B and the tongues 2 and 5 immediately commence to move downwards; as soon as 2 and 3 separate, however, the circuit 30 through relay B is broken so that 5 is free to move back again. After an interval of time depending on the inertia of the tongue and the tension of its restoring spring 5 and 6 will again make contact. 2 and 4 are already 35 in contact and a current therefore passes through the coil D. Now suppose the contacts T and M are only closed for a short period represented by a dot; as soon as T and M close the same thing happens as before, 40 viz: 2 moves instantly over to 4 and 5 moves away from 6 and then back again, but before 5 and 6 make contact the dot has ended and T and M and consequently 2 and 4 have opened, no current therefore passes through coil D.

45 The delay with this arrangement is the time taken by tongue 5 of relay 6 to make one swing, this is governed by the inertia of the tongue and the tension of the restoring spring.

If in addition to the coil to be energized 50 by dashes it is necessary that coil E of Figure 1 should be energized when a space equal to the interval between letters is received, a back contact S is provided for the tongue T so that a spacing relay may be energized when 55 tongue T makes contact with S to control the space magnet E.

Having described my invention, what I claim is:

60 1. In an electric calling device, in combination, a main relay adapted to be actuated by incoming signals, a slow-acting relay controlled by the main relay, an electromagnet controlled by the slow-acting relay, a second electromagnet in parallel with the slow-acting relay, a set of normally closed contacts in

series with both electromagnets, means whereby said contacts are selectively controlled by the magnets in accordance with the length of the received impulses, and an alarm shunted by said contacts, so that opening of the set of contacts by the electromagnets actuates the alarm.

2. In an electric calling device, in combination, an electromagnet energized by impulses corresponding to dashes only, a second electromagnet energized by impulses corresponding to both dots and dashes, a set of normally closed contacts in series with both electromagnets, means whereby said contacts are selectively controlled by the magnets in accordance 75 with the length of the received impulses, and an alarm shunted by said contacts, whereby upon opening of said contacts by the electromagnets the alarm is actuated.

3. In an electric calling device, the combination of an alarm and a magnet which is energized by relatively long electrical impulses only, a second magnet which is energized by both relatively long and relatively short electrical impulses a third magnet responsive to time intervals of relatively long duration, a disk carrying round its periphery a set of plungers, means operated by the first magnet to cause certain plungers to protrude from the disk, means actuated by the second magnet for rotating the disk through the angle between two plungers, means actuated by said third named magnet to cause certain other plungers to protrude from said disk and a set of contacts operatively associated 100 with said plungers and said alarm.

4. In an electric calling device, the combination of an alarm and a magnet which is energized by relatively long electrical impulses only, a second magnet which is energized by both relatively long and relatively short electrical impulses, a disk carrying round its periphery a set of plungers, means operated by the first magnet to cause plungers to protrude from the disk, means actuated by the second magnet for rotating the disk through the angle between two plungers and a set of contacts which are controlled by the plungers and which short circuit the alarm, another magnet energized on the occurrence 105 of an inter-letter space to actuate some of the plungers on the disk.

5. In an electric calling device, the combination of an alarm and a magnet which is energized by relatively long electrical impulses only, a second magnet which is energized by both relatively long and relatively short electrical impulses, a disk carrying round its periphery a set of plungers, means operated by the first magnet to cause plungers to protrude from the disk, means actuated by the second magnet for rotating the disk through the angle between two plungers and a set of contacts which are controlled by the plungers and which short circuit the alarm, 110 115 120 125 130

5 fingers carried by the disk adapted to lock the plungers and hold them protruded against spring action whereby they are maintained in proper sequence according to the sequence of the signal.

6. In an electric calling device, the combination of an alarm and a magnet which is energized by relatively long electrical impulses only, a second magnet which is energized by both relatively long and relatively short electrical impulses, a disk carrying round its periphery a set of plungers, means operated by the first magnet to cause plungers to protrude from the disk, means actuated by 10 the second magnet for rotating the disk through the angle between two plungers and a set of contacts, shunting said alarm, controlled by said plungers, the set of contacts being so arranged in front of the disk that 15 some contacts are normally closed while others are normally open.

7. In an electric calling device, in combination, an alarm, a magnet energized by impulses corresponding to dashes only, a second magnet energized by impulses corresponding to both dots and dashes, a set of contacts normally short-circuiting said alarm, plungers associated with said contacts, some of which are controlled by the two magnets, 20 and another magnet for controlling other of said contacts by means of said plungers, said last mentioned magnet being energized only on occurrence of inter-letter spaces.

8. In combination, a step by step rotating element, means for rotating the element a step each time an element of a signal is received, sliding means carried by the element, switching means carried on a stationary part and affected by the sliding means, actuating 35 means controlled by certain signals and intervals between signals for actuating the sliding means, locking means adjacent the sliding means for holding said sliding means in actuated position and means for rendering said locking means inoperative.

9. In combination, a step by step rotating element, means for rotating the element a step each time an element of a signal is received, sliding means carried by the element, switching means carried on a stationary part and affected by the sliding means, actuating 50 means controlled by certain elements of the signal for actuating the sliding means, locking means adjacent the sliding means for holding said sliding means in actuated position over a period of rotation of the rotating element, and releasing means for unlocking the locking means to release the sliding means to its original position for canceling the effect of incorrect signals, said releasing means determining the locking period of the locking means.

10. In combination, a step by step rotating element, means for rotating the element a step each time an element of a signal is re-

ceived, sliding means carried by the element, switching means carried on a stationary part and affected by the sliding means, actuating means controlled by certain elements of the signal for actuating the sliding means, locking means for the sliding means to hold the sliding means in actuated position over a period of rotation of the rotating element, and releasing means for unlocking the locking means to release the sliding means to its original position for canceling the effect of incorrect signals, said releasing means determining the locking period of the locking means, the switching means being so arranged as to produce a change of circuit conditions only when actuated by a proper sequence of signal elements through the sliding and locking means.

11. In combination, a step by step rotating element, means for rotating the element a step each time an element of a signal is received, sliding means carried by the element, switching means carried on a stationary part and effected by the sliding means, actuating means controlled by certain elements of the signal for actuating the sliding means, locking means for the sliding means to hold the sliding means in actuated position over a period of rotation of the rotating element, releasing means for unlocking the locking means to release the sliding means to its original position for canceling the effect of incorrect signals, the switching means being so arranged as to produce a change of circuit conditions only when actuated by a proper sequence of signal elements through the sliding and locking means, and alarm means operated by the switching means in response to change of circuit conditions.

12. In an electric calling device, in combination, a relay actuated by incoming signals, a slow acting relay controlled by the first relay, a magnet controlled by said slow acting relay, a second magnet in parallel with the slow acting relay, a set of contacts in series with both magnets, a signalling circuit including a source of power and an alarm normally short circuited by the set of contacts, and means controlled by said magnets in accordance with the signal impulses and intervals for relatively positioning the contacts of the set to remove the short circuit whereby the alarm is rendered operative.

13. In an electrical calling device, in combination, a relay actuated by incoming signals, a slow acting relay controlled by the first relay, a magnet controlled by said slow acting relay, a second magnet parallel with the slow acting relay, a set of contacts in series with both magnets, a signalling circuit including a source of power and an alarm normally short circuited by said set of contacts, and means operatively interposed between said contacts and said magnets and controlled by said magnets in response to a pre-

determined series of signals and intervals to position the contacts of the set to remove the short circuit and render the alarm operative.

14. In an electric calling device, the combination of a signalling circuit including a source of power and an alarm, a magnet energized by impulses corresponding to dashes only, a second magnet energized by impulses corresponding to both dots and dashes, a set 10 of contacts in series with both magnets and normally short circuiting said alarm, and means associated with said contacts and said magnets and controlled by said magnets for relatively positioning the contacts of the set 15 to remove the short circuit whereby the alarm is rendered operative.

15. In a signalling device, a signalling circuit including an indicating device and a source of power, means for normally short 20 circuiting said indicating device including a plurality of normally closed contacts, a signal relay, a slow acting spacing relay associated therewith, a spacing magnet associated with said spacing relay, a slow acting marking relay associated with said signal relay, a dash magnet associated with said marking relay, a ratchet control magnet in parallel 25 with said slow marking relay, a rotatable disk, a ratchet wheeled integral with said 30 disk, a ratchet interposed between said

ratchet control magnet and said ratchet wheel, a plurality of plungers slidably located around the periphery of said rotatable disk cooperating with said normally closed contacts, an armature interposed between 35 said dash magnet and the periphery of said disk, a second armature interposed between said space magnet and the periphery of said disk and means operated by said armatures in response to a predetermined signal for rotating said wheel and operating said plungers 40 to open all of said contacts.

16. In a signalling device, a signalling circuit including a source of power and indicating means, a plurality of contacts normally short circuiting said indicating means, a signal relay, switching means associated therewith, means associated with said switching means and said relay and responsive to time intervals of a predetermined duration to disassociate predetermined ones of said short circuiting contacts, a slow acting relay associated with said signalled relay and with said switching means, and means including means operated by said slow acting relay in response 50 to signalled impulses of predetermined duration to disassociate the remaining ones of said short circuit contacts.

WILFRED JOHN DAVIS.

determined series of signals and intervals to position the contacts of the set to remove the short circuit and render the alarm operative.

14. In an electric calling device, the combination of a signalling circuit including a source of power and an alarm, a magnet energized by impulses corresponding to dashes only, a second magnet energized by impulses corresponding to both dots and dashes, a set of contacts in series with both magnets and normally short circuiting said alarm, and means associated with said contacts and said magnets and controlled by said magnets for relatively positioning the contacts of the set to remove the short circuit whereby the alarm is rendered operative.

15. In a signalling device, a signalling circuit including an indicating device and a source of power, means for normally short circuiting said indicating device including a plurality of normally closed contacts, a signal relay, a slow acting spacing relay associated therewith, a spacing magnet associated with said spacing relay, a slow acting marking relay associated with said signal relay, a dash magnet associated with said marking relay, a ratchet control magnet in parallel with said slow marking relay, a rotatable disk, a ratchet wheeled integral with said disk, a ratchet interposed between said

ratchet control magnet and said ratchet wheel, a plurality of plungers slidably located around the periphery of said rotatable disk cooperating with said normally closed contacts, an armature interposed between said dash magnet and the periphery of said disk, a second armature interposed between said space magnet and the periphery of said disk and means operated by said armatures in response to a predetermined signal for rotating said wheel and operating said plungers to open all of said contacts.

16. In a signalling device, a signalling circuit including a source of power and indicating means, a plurality of contacts normally short circuiting said indicating means, a signal relay, switching means associated therewith, means associated with said switching means and said relay and responsive to time intervals of a predetermined duration to disassociate predetermined ones of said short circuiting contacts, a slow acting relay associated with said signalled relay and with said switching means, and means including means operated by said slow acting relay in response to signalled impulses of predetermined duration to disassociate the remaining ones of said short circuit contacts.

WILFRED JOHN DAVIS.

CERTIFICATE OF CORRECTION.

Patent No. 1,719,535.

Granted July 2, 1929, to

WILFRED JOHN DAVIS.

It is hereby certified that error appears in the printed specification of the above numbered patent requiring correction as follows: Page 5, line 98, claim 11, after the word "signals" insert the words "said releasing means determining the locking period of the locking means"; and that the said Letters Patent should be read with this correction therein that the same may conform to the record of the case in the Patent Office.

Signed and sealed this 18th day of February, A. D. 1930.

(Seal)

M. J. Moore,
Acting Commissioner of Patents.
